DESIGN FOR LACE

George Dunlap Boysen, Philadelphia, Pa., assignor
to New England Lace Mills, Inc., New York,
N. Y.

Application October 20, 1934, Serial No. 53,712

Term of patent 3½ years

To all whom it may concern:

Be it known that I, George Dunlap Boysen, a citizen of the United States, residing at Philadelphia, in the county of Philadelphia, and State of Pennsylvania, have invented a new, original, and ornamental Design for Lace, of which the following is a specification, reference being had to the accompanying drawing, forming part

thereof in which the figure is a face view of a piece of lace showing my new design

I claim:

The ornamental design for lace substantially as shown.

In testimony whereof I affix my signature.

GEORGE DUNLAP BOYSEN.
